UNITED STATES PATENT OFFICE.

MOSES BOGUSHEFSKY, OF NEW YORK, N. Y.

CAR-FENDER.

No. 897,708.

Specification of Letters Patent.

Patented Sept. 1, 1908.

Application filed April 18, 1908. Serial No. 427,779.

To all whom it may concern:

Be it known that I, MOSES BOGUSHEFSKY, a subject of the Czar of Russia, and a resident of the city of New York, borough of Brooklyn, in the county of Kings and State of New York, have invented a new and Improved Car-Fender, of which the following is a full, clear, and exact description.

This invention relates to car fenders such as carried by street railway cars or trolley cars in order to prevent accidents.

The object of the invention is to produce a fender of simple construction, having improved means for throwing the body into its cradle or basket.

More specifically, the invention contemplates a construction comprising a transverse bar or yoke normally held in an elevated position above the cradle at or near the ground line, and just before the cradle a movable part is provided which operates automatically to depress the yoke or bar and draw the same toward the cradle in such a way as to throw the body standing before the cradle rearwardly so that it will fall into the cradle.

The invention consists in the construction and combination of parts to be more fully described hereinafter and particularly set forth in the claims.

Reference is to be had to the accompanying drawings forming a part of this specification, in which similar characters of reference indicate corresponding parts in all the figures.

Figure 1 is a perspective showing a portion of the forward end of a car to which my fender is applied; Fig. 2 is a vertical sectional side elevation, showing the device in its normal position and ready to be operated by a body which is struck by the fender; Fig. 3 is a view similar to Fig. 2, but showing the fender in its closed or operating position; Fig. 4 is a view similar to Fig. 3, but showing certain parts removed and broken away, and showing other parts in cross section so as to further illustrate the construction of the device; Fig. 5 is a rear elevation of the framing of the fender at one side, the upper parts of the framing being broken away; and Fig. 6 is a cross section on the line 6—6 of Fig. 2, and illustrating the means for guiding the operating member on the frame of the fender.

Referring more particularly to the parts, 1 represents the forward bumper of the car to which the fender 2 is attached. The fender 55 comprises side plates or knees 3 having elongated vertical legs 4 which are attached by

means of angle plates 5 to the bumper 1, as indicated. These knees 3 are held securely in position by side braces 6 which extend down from the body of the car and are secured in lugs 7 on the outer sides of the knees as shown. These knees afford means for supporting the cradle or basket 8 the body of which is formed of netting or similar material, and this netting is supported on a frame 60 9. This frame has a vertical extension presenting oppositely disposed parallel side bars connected by a horizontal bar, and this vertical extension is formed integrally with a horizontal extension 10 which is formed by 65 bending the lower end of the vertical extension forwardly. This horizontal extension of the frame of the cradle lies near the bed of the track, as illustrated. The cradle frame 9 is attached to the knees 3, and in addition to 70 this it is provided on its rear side with brackets 11 which are attached to the under side of the forward bumper 1, as indicated in Fig. 2.

Disposed forwardly of the horizontal extension 10 of the cradle, I provide a trip bar 80 12; which extends transversely of the track and is formed with parallel side arms 13 as shown. On their under sides these side arms 13 are provided with T-shaped tongues 14, and these tongues 14 slide longitudinally in 85 guides 15 formed on the upper sides of the side bars of the horizontal extension 10. Just beyond these guides 15 the arms 13 have long reduced necks 16, and these necks pass through guide clips 17 which are attached to 90 the lower part of the vertical extension of the cradle frame, as indicated most clearly in Fig. 4. Beyond these guide clips 17 the necks 16 are provided with outwardly projecting pins 18, and these pins pass through 95 slots 19 which are formed in the short arms of the levers 20 which are pivoted at 21 to the sides of the cradle frame. Between the guide clips 17 and the enlarged portion of the arms 13, helical springs 22 are provided, 100 which tend to hold the trip frame in a forwardly extended position, as will be readily understood. The upper ends of the levers 20 are formed into guides or sheaths 23, and the upper portions of these sheaths are connect- 105 ed by a brace or cross bar 24.

Mounted to slide longitudinally in the sheaths 23 I provide slide bars 25, and the upper ends of these slide bars project beyond the sheaths and incline upwardly as indicated. Their extremities are connected by a yoke or cross bar 26 which is covered with

rubber or similar material, which will prevent it from injuring the body which it strikes. The lower ends of the slide bars 25 project from the lower ends of the sheaths 23, 5 as shown, and are pivotally attached to rocker plates 27. These rocker plates are crescent-shaped as shown, and are pivotally attached at 28 to the sides of the horizontal extension of the cradle frame. They project 10 forwardly from their pivot points as shown, and are provided with inclined slots 29. These slots receive pins 30 which project outwardly from the sides of the arms 13, as indicated most clearly in Figs. 2 and 3.

15 The operation of the fender will now be described: A body standing on the track strikes the trip bar 12, which normally occupies the advanced position shown in Fig. 2, at which time the yoke 26 is supposed to be held at a 20 high elevation. When the trip bar 12 is struck it slides rearwardly on the cradle frame and rocks the upper ends of the levers 20 forwardly. This depresses the yoke 26; at the same time the pins 30 operate through 25 the medium of the slots 29, to rock the rocker plates 27 so that their rear ends are depressed. In this way the slide bars 25 are slid inwardly in the sheaths 23. In this way the yoke 26 not only moves downwardly but 30 it moves inwardly toward the cradle. In this way it operates to strike the upper part of the body so as to force the body rearwardly and into the cradle.

Having thus described my invention, I 35 claim as new and desire to secure by Letters Patent:

1. In a car fender, in combination, a cradle adapted to catch a body, a movable trip bar projecting forwardly and adapted to be struck by a body on the track, a yoke normally held in an elevated position, and means actuated by said trip bar for moving said yoke downwardly and rearwardly toward said cradle.

45 2. In a car fender, in combination, a cradle adapted to catch a body, a trip bar projecting before said cradle, means for guiding said trip bar to slide in a front and rear direction, levers mounted at the sides of said cradle 50 and projecting upwardly and forwardly, a yoke connecting said levers and normally disposed in an elevated position, and a connection between said levers and said trip bar for depressing said yoke when said trip bar 55 is struck.

3. In a car fender, in combination, a cradle adapted to catch a body, a trip bar guided to slide on said cradle, levers pivotally mounted at the sides of said cradle and constituting 60 guides, slide bars guided on said levers and projecting upwardly and forwardly, a yoke

connecting said slide bars and normally disposed in an elevated position, means actuated by said trip bar for rocking said levers, and means actuated by said trip bar for 65 sliding said slide bars upon said levers.

4. In a car fender, in combination, a cradle adapted to catch a body, a trip bar projecting forwardly therefrom and guided on said cradle, levers pivotally mounted on the sides 70 of said cradle and projecting upwardly and forwardly therefrom, means for connecting said trip bar with said levers for rotating the same, slide bars guided on said levers, rocker plates pivotally connected with said slide 75 bars and pivotally mounted on said cradle, means connecting said trip bar with said rocker plates for sliding said slide bars, and a yoke connecting the upper ends of said slide bars and moving downwardly and rearwardly when said trip bar is struck.

5. In a car fender, in combination, a cradle, a trip bar mounted to slide rearwardly on said cradle and projecting before the same, levers pivotally mounted on the sides of said 85 cradle and projecting upwardly and forwardly therefrom, a pin-and-slot connection between said trip bar and said levers for actuating said levers, slide bars slidably mounted on said levers and projecting upwardly 90 and forwardly, a yoke connecting said slide bars, rocker plates connected with said slide bars to move the same on said levers, said rocker plates being mounted on said cradle, and a pin-and-slot connection between said 95 cradle and said trip bar for actuating said yoke.

6. In a car fender, in combination, a cradle, a trip bar mounted to slide rearwardly on said cradle and projecting before the same, 100 levers pivotally mounted on the sides of said cradle and projecting upwardly and forwardly therefrom, a pin-and-slot connection between said trip bar and said levers for actuating said levers, slide bars slidably mounted 105 on said levers and projecting upwardly and forwardly, a yoke connecting said slide bars, rocker plates connected with said slide bars to move the same on said levers, said rocker plates being mounted on said cradle, a pin- 110 and-slot connection between said rocker plates and said trip bar for actuating said yoke, and springs normally holding said trip bar in a forwardly disposed position.

In testimony whereof I have signed my 115 name to this specification in the presence of two subscribing witnesses.

MOSES BOGUSHEFSKY.
